UNITED STATES PATENT OFFICE.

CHARLES GLANTZ, OF ARKVILLE, NEW YORK.

FOLDING CHAIR.

Application filed February 21, 1925. Serial No. 10,879.

To all whom it may concern:

Be it known that I, CHARLES GLANTZ, a citizen of the United States, residing at Arkville, county of Delaware, State of New York, have invented certain new and useful Improvements in Folding Chairs, of which the following is a specification.

My invention relates to folding chairs, and has for its objects, first, to provide an improved construction which in its folded position will present a width not greater than that of the main or front leg thereof, and, secondly, which in both the open or folded positions will be retained as to its movable parts against any loose play.

These objects I accomplish in the manner and by the means hereinafter described and claimed, reference being had to the accompanying drawing, in which:—

20 Figure 1 is a perspective view of my improved chair, shown in the open or unfolded position.

Figure 2 is a side elevation of the same folded.

25 Figure 3 is an enlarged detail sectional view taken on the line III—III of Figure 1.

Figure 4 is a similar view taken through one of the rear legs.

30 Figure 5 is a detail view of a portion of the inner face of one of the rear legs and the chair seat, the latter being shown in the open position.

Figure 6 is a similar view with the chair seat shown in its closed position.

35 Similar numerals of reference denote corresponding parts in the several views.

In the said drawing, the reference numerals 1 denote the front legs of my improved chair, the usual seat 2 being pivoted thereto by means of bolts 3 engaging the sides of said seat intermediate its width, as shown. Pivoted to the front legs 1 at 4 are the rear legs 5, and attached to the inner face of each of said rear legs is a metal plate 6 formed with a longitudinal slot 7 therein, said slot being disposed at a slight angle to the length of said plate, and at its upper end being tapered at 8, as best seen in Figure 5. Screwed to each side of the seat 2 at its rear 50 is a plate 9 having its edges overlapping the upper and lower faces of the seat as seen in Figure 4, said plates each being formed with an out-struck lug 10. As shown in

Figure 5, said lugs are disposed to lie at a right angle to the seat 2, and are of a width 55 to fit snugly in the slot 7 in plate 6 when the seat is turned to the position shown in Figure 6. But when the seat is moved to its open position, shown in Figure 5, said lugs 10 will be given a quarter turn and will 60 move up into the tapered portions 8 of said slots 7, and will wedge therein, as shown in Figure 5.

In use when the chair is in its open position, the lugs 10 will lie in the upper portions of the slots 7 and due to the fact that they are turned to substantially vertical position will snugly fit said slots, thereby retaining the legs 5 rigidly in their adjusted position. To fold the chair, the seat 2 is 70 lifted at the front, and the same swinging on its pivots 3 will cause its rear end to descend, thereby turning the lugs 10 gradually in the slots 7, the downward movement thereof forcing the legs 5 towards 75 the legs 1, and the inclined disposition of said slots 7 ultimately will force said legs 5 into position to lie substantially parallel with the legs 1, so as to be concealed thereby when the seat 2 reaches its vertical position. At the same time the lugs 10, as the seat 2 reaches its extreme vertical position, will be turned to substantially horizontal 80 position and will snugly fit the slots 7, as shown in Figure 6, thereby locking the legs 85 5 in their closed position, as readily will be understood.

I have shown my improved chair as embodying legs 2 joined at their upper ends by a cross piece 11, but it will be understood 90 that the same may be made of bent wood if desired, and in one piece. It will also be understood that the front legs 1 are provided with the usual lower cross piece 12, and in a similar manner the lower portions 95 of the legs 5 are connected by a cross piece 13.

Having thus fully described my invention, what I claim as new and desire to secure by Letters Patents, is:—

1. A folding chair, embodying front legs, rear legs pivoted thereto at their upper ends, a seat pivoted intermediate its length between said front legs, and means forming sliding connections between the rear of said 105 seat and said rear legs, said means forming

a loose engagement in intermediate positions of the seat and legs, but adapted to lock the two together at each extreme of adjustment.

2. A folding chair, embodying front legs, rear legs pivoted thereto at their upper ends, a seat pivoted intermediate its length between said front legs, flat lugs on the rear of said seat, and slotted plates on said

rear legs engaged thereby, said slots being tapered at their upper ends, said lugs when the seat is open fitting said tapered portions edgewise, and when said seat is folded fitting said slots transversely.

In testimony whereof I hereunto affix my signature.

CHARLES GLANTZ.
